UNITED STATES PATENT OFFICE.

SYDNEY E. SINCLAIR AND HENRY B. SOUTTER, OF CEDAR RAPIDS, IOWA.

DESIGN FOR A PINCUSHION.

SPECIFICATION forming part of Design No. 31,301, dated August 1, 1899.

Application filed July 10, 1899. Serial No. 723,423. Term of patent 7 years.

To all whom it may concern:

Be it known that we, SYDNEY E. SINCLAIR, a subject of the Queen of Great Britain, and HENRY B. SOUTTER, a citizen of the United States, residing at Cedar Rapids, in the county of Linn and State of Iowa, have invented and produced a new and original Design for Pincushions, of which the following is a full and clear description.

10 In the accompanying drawings, forming a part of this specification, Figure 1 is a front or plan view of a pincushion, illustrating our new design. Fig. 2 is a side view of the same as seen from the direction indicated by the 15 arrow, Fig. 1.

The leading or material feature of our design is the peculiar outline and contour given to the cushion, as shown in the drawings.

The upper portion of the design, as shown 20 in Fig. 1, forms about two-thirds of an approximate circle surmounted by a loop A. At B the circle is projected as a tangent to C. Thence the outline extends in an irregular curve to D, the lower end of the figure being 25 much smaller than the upper end. From D the outline extends in a reverse curve to a

point where it merges with the larger circle at E. The general contour is that of a nicely-trimmed canvas-covered ham, which the design is intended to simulate. Except between 30 the points B C, represented by a straight line, the extreme margin of the figure gives the appearance of a narrow cord or seam F.

As seen from the side and as shown in Fig. 2, the design shows a regular figure rounded 35 at the top and bottom, tapering downwardly, surmounted by a loop, and intersected longitudinally by an overcast seam, presenting to the eye the appearance of such a seam or a cord.

Having thus described our invention, what we claim as new, and desire to secure by Letters Patent, is—

The design for a pincushion, as herein shown and described.

In testimony whereof we affix our signatures in presence of two witnesses.

SYDNEY E. SINCLAIR.
HENRY B. SOUTTER.
